UNITED STATES PATENT OFFICE

117,787

DESIGN FOR A GAME BOARD

Anthony Guerra, Hackensack, N. J.

Application March 27, 1939, Serial No. 83,849

Term of patent 3½ years

To all whom it may concern:

Be it known that I, Anthony Guerra, a citizen of the United States, residing at Hackensack, in the county of Bergen and State of New Jersey, have invented a new, original, and ornamental Design for a Game Board, of which the following is a specification, reference being made to the accompanying drawing, forming part thereof.

The figure is a plan view of the game board showing my new design.

The article is of no appreciable or substantial thickness.

I claim:

The ornamental design for a game board, as shown and described.

ANTHONY GUERRA.
